MOBILE HOT WATER HOUSE HEATER

John M. Loveless, Somerville, Ind., assignor to
George H. Atkin, Evansville, Ind.

Application November 9, 1939, Serial No. 303,673

3 Claims. (Cl. 126—101)

This invention relates to a portable hot water heater.

The invention aims to provide, in a manner as hereinafter set forth, a heater of the class referred to capable of being conveniently and expeditiously positioned at any desirable point for effective heating purposes.

This invention further aims to provide, in a manner as hereinafter set forth, a hot water heater including means for pre-heating air and means for expelling the pre-heated air between hot water conducting tubes of a radiator into the space surrounding the heater thereby increasing the temperature of such space.

15 The invention further aims to provide, in a manner as hereinafter set forth, a portable hot water heater whereby convenient access may be had to the interior thereof when occasion requires.

20 The invention further aims to provide, in a manner as hereinafter set forth, a portable hot water heater which is comparatively simple in its construction and arrangement, strong, durable, compact, readily assembled, conveniently shifted from point to point, thoroughly efficient in its use, comparatively inexpensive to manufacture and operate, using a liquid or gaseous fuel as the heating element, and eliminating the use of coal, coke or hard fuels commonly used in stoves and 25 furnaces.

30 Embodying the aims aforesaid, and others which may hereinafter appear, the invention consists of the novel construction, combination and arrangement of parts as will be more specifically described and illustrated in the accompanying drawings, wherein is shown an embodiment of the invention, but it is to be understood that changes, variations and modifications may be resorted to which fall within the scope of the 35 invention as claimed.

40 In the drawings:

Figure 1 is an elevation looking towards one of the sides of the heater.

Figure 2 is a front elevation of the heater.

45 Figure 3 is a section on line 3—3 Figure 2.

Figure 4 is a section on line 4—4 Figure 3.

Figure 5 is a section on line 5—5 Figure 3.

Figure 6 is a section on line 6—6 Figure 3.

50 Figure 7 is a section on line 7—7 Figure 1, and

Figure 8 is a section on line 8—8 Figure 3.

The heater includes a housing A having a closed top and bottom and mounted at the front and rear of its bottom on spaced aligned caster 55 wheels or rollers B. The housing comprises a

frame 1, which includes a pair of oppositely disposed spaced parallel upright front frame members 3 of angle-shaped cross section, a pair of oppositely disposed spaced parallel upright rear frame members 4 of angle-shaped cross section, a pair of upper spaced parallel side braces 5 of angle-shaped cross sections connecting the members 3 to the members 4, a rear upper brace 6 aligned with the braces 5, of angle-shaped cross section and connecting the members 4 together, a front upper brace 7 aligned with the braces 5 of angle-shaped cross section connecting the braces 5 together rearwardly of the members 3, a rear intermediate brace 8 connecting the members 4 together, and a pair of 15 intermediate side braces 9 connecting the members 3 to the members 4. The braces 5, 6 and 7 are arranged below the upper ends of the members 3, 4 and they cooperate to provide a support for a purpose to be referred to. 20

The housing also includes a bottom wall 2, a top wall 10, a front wall 11, a pair of side walls 12, 13 and a rear wall 14, and the walls 11, 12, 13, 14 are suitably secured to and are disposed exteriorly of frame 1. The walls 11, 12, 13 and 14 do not depend below the lower ends of the members 3, 4. The wall 10 is suitably secured to and is arranged between the upper ends of the walls 11, 12, 13, 14. The wall 10 is imperforate. The wall 11 has its upper portion formed with an enlarged opening 15. Each of the side walls is formed of two sections 16, 17 (Figure 1) and with the section 17 formed with an enlarged opening 18 for receiving section 16. The latter constitutes a door for closing the opening 18 and it is hinged at its lower end to section 17, as at 19. A latch 20 is carried by section 17 for releasably retaining section 16 in closed relation with respect to opening 18. The latter is arranged in upper portion of section 17. 35 The section 16 is provided with a handle 21. The rear wall 14 has a portion thereof formed of a hinged door 21a and below the latter with an enlarged opening 22 constituting an intake. 40

Arranged within the space 23 formed between the braces 5, 6 and 7 and the top wall 10, as well as being supported by such braces is a water tank 24 provided with an angle-shaped filling pipe 25, which extends through the rear wall 26 of tank 24 and opens into the latter. 45 The pipe 25 extends outwardly through and then upwardly with respect to the upper portion of wall 14. The upper end of pipe 25 has detachably secured thereon a safety valve device 27 (Figure 8). 50 55

The forward portion of the bottom 28 of the tank 24 is arranged forwardly of brace 7 and opens into the upper end of a vertically disposed radiator 29 arranged inwardly of and extending 5 across the opening 15. The lower end of the radiator 29 opens into a water receiver 30 arranged below opening 15 and inwardly of wall 11. The radiator 29 is positioned between brace 7 and wall 11 and depends slightly below the 10 bottom of opening 15. The radiator is secured to the bottom of tank 24 and to the top of the receiver 30. The latter may, if desired, be secured to frame 1. Disposed in forwardly extending relation with respect to the radiator 29 is a 15 grating, lattice or screen 31 therefor. The grating is flanged, as at 32 and with the flange secured to the portion of the inner face of the wall 11 bordering the opening 15.

Arranged within the frame 1 and disposed in spaced relation with respect to the said front, rear and side wall, as well as being spaced from the tank 24 is a vertically disposed cylinder 33 having an open top portion 34 and an open bottom 35. The cylinder 33 is disposed rearwardly 25 of the vertical axis of frame 1, and includes a stationary section 36 and a hinged latchable section 37, which is independent of the top portion 34. The latter is integral with and disposed in lateral relation with respect to the upper end of 30 the said section 36. Arranged within and having the major portion thereof disposed in spaced relation to the inner face of the cylinder 33 is a vertically disposed water heating coil 38. The upper end of the coil is arranged below the said 35 top portion 34. The lower end of the coil is arranged above the lower open bottom 35 of the cylinder 33. The upper and lower ends of the coil 38 are formed with substantial lateral extensions 39, 40 respectively which extend outwardly 40 through the section 36 of cylinder 33 and are connected by the couplings 41, 42 respectively to a hot water delivery pipe and a water return pipe 43, 44 respectively. The pipe 43 leads from the extension 39 and opens into the tank 24. The 45 pipe 44 leads from the receiver 30 to the extension 40. The pipe 43 extends through and is connected to the bottom of tank 24. The pipe 44 extends through and is connected to the rear wall of receiver 30. The extensions 39, 40, couplings 41, 42, pipes 43, 44, bottom of tank 24, rear 50 wall of receiver 30 and stationary part of cylinder 33 cooperate to suspend the cylinder within support 1 and to suspend the coil within the cylinders.

55 Arranged rearwardly of and in proximity to the radiator 29 is a motor driven fan 45 for forcing heated air through the radiator and grating for discharge from the front of the heater for heating purposes. The fan hub is indicated at 60 46 and is connected to the shaft 47 of an electric motor 48 suspended in the support 1 rearwardly of the fan 45.

The suspension for motor 48 includes a strap 49 formed at each end with a depending flange 65 50 having an opening 51. The strap 49 is secured to the lower face of the bottom 28 of tank 24 by the holdfast means 52 (Figure 6). The flanges 51 constitute hangers and depending therefrom is a V-shaped suspension member 53 formed of 70 a bight 54 and a pair of oppositely outwardly inclined arms 55 having hook-shaped upper portions 56 for detachably connecting them to the flanges 51. The body or the casing of motor 48, is seated intermediate its ends on the bight 54, 75 and there is correlated with the latter a clamping

means 57 for fixedly securing the motor 48 to member 53. The means 57 consists of a strap having an arcuate central portion 58 and a pair of oppositely outwardly inclined end portions 59, which bear against the inner faces of the arms 5 55. The bight 54 is substantially of semi-circular contour and constitutes a clamping part. The portion 58 of the means 57 also constitutes another clamping part. The motor at one side is positioned against the bight 54, after which the 10 portion 58 of the means 57 is positioned tightly against the opposite side of the motor, the end portions 59 of the means 57 are then secured to the arms 55 by the holdfast means 60 whereby the motor is clamped to said means 57 and suspended in support 1 rearwardly of the radiator 29.

The cylinder 33 provides a heating chamber 61 for the coil 38. There is correlated with the open bottom of chamber 61 a heating means for coil 38 and by way of example such means will 20 be in the form of a regulatable self-feeding oil, liquid fuel or gas burner 62. The burner 62 is to be positioned on the bottom wall 2 of housing A, arranged within the support 1, aligned with and extended to a point in close proximity to the 25 open bottom of cylinder 33.

The heater includes a fan chamber 62^a for the air and which is provided by an inclined partition 62^b correlated with the walls 12, 13, radiator 29 and tank 24. The partition 62^b extends at a 30 rearward upward inclination from the receiver 30 to the cylinder 33 to a point below and in proximity to the end portion 39 of coil 38. The direction of the travel of the air is indicated by arrows, Figure 3. The direction of travel is such 35 that the air will be pre-heated before it is expelled through the radiator by the fan.

The side wall 13 is formed with a plug 63 from which lead power circuit lines, not shown, to the motor 48. The plug 63 is adapted to be connected 40 to a source of electrical energy, not shown. Connected to the wall 13 and communicating with the tank 24 is a temperature gage 64 and a water level gage 65 of the float operated type.

On the heating of the coil 38 a circulation of 45 hot water will be had from the coil through respectively the tank 24, the radiator 29 and the receiver 30 and then through pipe 44 to the coil. As the fan is operating simultaneously on the heating of and during the circulation of the hot 50 water the air drawn into the heater through opening 22 will be heated and discharged from the interior of the heater through the radiator 29 which also acts to heat the air.

What I claim is:

1. In a hot air heater of that type including a hot water circulating system for heating pre-heated air and a heating means for preheating air and the water of said system, the combination of a housing for enclosing and supporting 60 said system and means, said housing having front and rear openings for the passage of air therethrough, the said front opening being arranged above the rear opening, inclined baffle means arranged within the forward portion of the housing, 65 aligned with the lower portion of the front opening, extending above the height of said rear opening and coacting with the housing, said system and said heating means to provide a fan chamber open at its front and rear, and a motor driven 70 unit including a fan in said chamber aligned with said front opening, and means adapted to be secured to a part of said system for suspending said unit within said chamber.

2. In a hot air heater for the purpose set forth, 75

a housing formed with a cool air intake at its rear and a heated air outlet at its front arranged above said intake, a hot water circulation system within the housing for heating preheated air including a tank, a coil and a radiator opposing said outlet, heating means within the housing for preheating the incoming air and for heating the water of said system spaced rearwardly from said outlet, disposed below said tank and having said coil arranged therein, an upwardly disposed baffle member inclining rearwardly from its lower to its upper end within the housing, said member being connected at its upper end to said heating means, at its lower end with said radiator, said member coacting with said housing, said heating means and said tank to form an open rear and open front fan chamber, a unit consisting of a motor driven fan structure within said chamber and aligning with said outlet, and means secured to said tank for suspending said structure.

3. In a hot air heater for the purpose set forth, a housing having a cool air intake in its rear and a heated air outlet in its front arranged above said intake, a hot water circulating system within

the housing for heating preheated air including a tank above said intake, a radiator rearwardly of and in juxtaposition to said outlet, a receiver below said outlet and a coil disposed below the tank rearwardly of the radiator and receiver, a vertically disposed heating means for preheating the incoming air and for heating the water of said system to provide for the latter heating the preheated air, said heating means encompassing said coil, an upwardly disposed baffle member inclining rearwardly from its lower to its upper end, secured at its lower end to said receiver and at its upper end to the upper part of said heating means, said member coacting with said housing, said tank and heating means to provide an open rear and an open front chamber arranged in the upper part of the front portion of the housing in alignment with said outlet, a unit consisting of a motor driven fan structure arranged in said chamber in alignment with said outlet, and means secured to said tank for suspending said unit in said chamber.

JOHN M. LOVELESS.

CERTIFICATE OF CORRECTION.

Patent No. 2,254,869.

March 11, 1941.

JOHN M. LOVELESS.

It is hereby certified that the above numbered patent was erroneously issued to George H. Atkin, as assignee of the entire interest therein, whereas said patent should have been issued to the inventor, John M. Loveless, and George H. Atkin assignee of one-half interest, as shown by the record of assignments in this office; and that the said Letters Patent should be read with this correction therein that the same may conform to the record of the case in the Patent Office.

Signed and sealed this 15th day of April, A. D. 1941.
